W. S. RUSSELL,
AUTOMATIC TYPE CABINET.
APPLICATION FILED FEB. 3, 1921.

1,393,317.

Patented Oct. 11, 1921.

Fig. 1.

UNITED STATES PATENT OFFICE.

WILLIAM S. RUSSELL, OF ST. LOUIS, MISSOURI.

AUTOMATIC TYPE-CABINET.

1,393,317.

Specification of Letters Patent. Patented Oct. 11, 1921.

Application filed February 3, 1921. Serial No. 442,072.

To all whom it may concern:

Be it known that I, WILLIAM S. RUSSELL, a citizen of the United States, residing at St. Louis, in the State of Missouri, have 5 invented certain new and useful Improvements in Automatic Type-Cabinets, of which the following is a specification containing a full, clear, and exact description, reference being had to the accompanying drawings, forming a part hereof.

My invention consists in the novel disclosure hereinafter particularly described and distinctly claimed.

The object of my invention is to provide 15 an improved automatic type-cabinet for delivering type from magazine-galleys to the fingers of the compositors; whereby much time of the compositors will be saved, in handling the product of monotype machines.

20 A further object of my invention is to provide inclined magazine-galleys, into the open end of which the type are run from the type-machine; whereby the compositor's fingers may quickly grasp the type at the lowermost end and edge of said magazine-galleys, and be enabled to remove the type quickly, as wanted, from the delivery-end of said magazine-galleys.

25 A further object of my invention is to provide a magazine-galley which will hold more type than the present case-system.

30 A further object of my invention is to provide a magazine-galley system, which will do away with the present laborious way 35 of sorting cases, and will give the monotype operator more time to produce type, as he will not have to lay the type in sort-cans, which my invention does away with altogether.

40 A further object of my invention is to provide an improved magazine-galley system of delivering type to compositors; whereby half-a-dozen or more compositors can set type from the same type-cabinet at 45 one time, and not interfere with each other, and not have to lose time by standing around while a single compositor has a case pulled out of the cabinet, and has blocked all of the cases above and below the one he has 50 pulled out.

In the drawing,

Figure 1 is a fragmentary front-elevation of a type-cabinet containing a series of magazine-galleys, the latter being shown in 55 perspective, on account of their inclined position.

Fig. 2 is a detail view of a portion of the lower end of one of my magazine-galleys, detached, and

Fig. 3 is a detail section of the lower (or 60 delivery) end of one of my magazine-galleys, the section being taken on line 3—3 of Fig. 2.

In carrying out my invention, I provide a suitable cabinet or casing composed of 65 vertical sides, such as 1, a series of inclined shelves 2, and an inclined top 3, all put together in a workman-like practical manner, and having its front and rear open between said shelves, so that the series of magazine-galleys 4 may be inserted from the rear, and rest in the cabinet upon their lowermost edges, in contact with said shelves.

The said magazine-galleys 4 are to be supported in the cabinet upon their lower 75 edges, which are inclined downwardly toward the front at an angle of at least 45 degrees, so that the type 5 that are in said magazines will gravitate to the front (or delivery-end) of the same.

Said magazine-galleys are also inclined, or tipped, laterally, as shown, so that the said type will gravitate to the lower edge as well as the lower front end and bottom 85 of said magazines, and with the base ends of the type in contact with the said bottom.

Laterally and longitudinally inclined vertical partitions 7, act as a lateral support for said magazines, which rest in contact therewith.

90 There is a space 8 between the adjacent partitions 7, to afford access of the compositor's fingers, in removing the type from the delivery-end of the magazines.

The front ends of said magazines 4 are 95 marked with the style of the type, as "K," "L," "M," &c., for an obvious purpose.

A horizontal barrier 9, in the form of a wire or bar, extends across the open front spaces 8 a slight distance above the said inclined shelves 2, to act as a stop for the magazines, and to prevent same from sliding out of the cabinet.

The front (or delivery) ends of the said 105 magazines 4 are cut off at an angle, or are on the bias, as shown in Figs. 2 and 3, so that said ends will stand approximately vertical when said magazines are in place in the cabinet.

The rear ends are also preferably cut off 110 at the same angle as the front ends, so that both front and rear ends will be parallel

and will stand in a vertical position, notwithstanding the fact that the said magazines are inclined, as previously stated.

Rectangular stop-blocks 10 are located in 5 the angular front ends of said magazines, to support type 5 at the delivery-ends of said magazines at a right-angle to the bottom 6 thereof.

A roller 11 is mounted on a pindle 12, in 10 a recess 14 formed in each of said rectangular stop-blocks 10, and the upper portion of said roller projects in the path of the descending type 5, and acts to lift the front one of a line of type a slight distance above 15 the remaining type of said line, as shown in Fig. 3, so that said front type will project a sufficient distance to be conveniently grasped by the fingers of the compositor, and enable him to remove said elevated type 20 without fumbling, or loss of time.

Common smooth leads 15 are placed between the adjacent lines of type 5, as they come from the monotype machine and are run into the said magazines 4, so that the 25 type of the upper lines will slide with the least friction upon the line below, as delivery is being made at the delivery-end of said magazines.

30 *The operation.*

First, the cabinet is provided, as above described, for holding the magazines at the required angle to automatically feed the type to the delivery-ends of said magazines.

35 Then, the series of magazines are filled with lines of type, by running the latter into the open rear end of said magazines, direct from the type-machine, or by hand, or otherwise.

40 Then, the filled magazines are set upon

edge, leaned slightly to one side, and inclined downwardly from their rear ends to their delivery-ends, in said cabinet, and

Finally, the type are removed, as wanted by the compositors, at the extreme front, 45 or lowermost, end of said magazines.

I do not limit myself to the exact form of the invention herein shown and described, as skilled mechanics can readily make changes which will not be a departure from 50 the scope of following claims.

I claim:

1. A type-magazine having its front end cut off at such an angle that the angular front end will stand in a vertical plane when 55 the magazine is inclined downwardly both from its rear end to its front end and laterally from edge to edge, a rectangular stop-block in the said angular front end, and a roller mounted in a recess in said stop-block and projecting into the path of the type as they gravitate to said stop-block.

2. An automatic type-delivering cabinet, composed of a suitable casing; type magazine supporting means in said cabinet inclined toward both the front and bottom thereof; and a series of type magazines 65 removably supported partly on edge in said cabinet by said inclined supporting means, and inclined longitudinally and laterally 70 from the back of said cabinet toward the front thereof.

In testimony whereof, I have signed my name to this specification in presence of two subscribing witnesses.

WILLIAM S. RUSSELL.

Witnesses:

JOHN C. HIGDON,
HENRY L. HIGDON.
